UNITED STATES PATENT OFFICE.

JAMES CLARKE HAGEY, OF CHICAGO, ILLINOIS, ASSIGNOR TO THE CABLE COMPANY,
OF CHICAGO, ILLINOIS, A CORPORATION OF ILLINOIS.

WIND-SUPPLYING APPARATUS FOR MUSICAL INSTRUMENTS AND MUSICAL- INSTRUMENT PLAYERS.

1,247,265.

Specification of Letters Patent. Patented Nov. 20, 1917.

Application filed February 26, 1908. Serial No. 417,851.

To all whom it may concern:

Be it known that I, JAMES CLARKE HAGEY, a citizen of the United States, residing at Chicago, in the county of Cook and State of Illinois, have invented new and useful Improvements in Wind-Supplying Apparatus for Musical Instruments and Musical-Instrument Players, of which the following is a specification.

- 10 My invention relates to musical instruments such as organs, pianos supplied with automatic player-devices and to devices for automatically playing musical instruments and particularly concerns the apparatus 15 comprised in instruments of this kind for supplying and maintaining the desired degrees of operating air-tension or pressure.
- 20 The object of my invention is to provide apparatus which may be easily secured in or removed from operative position within the case of the instrument and to eliminate the troublesome connecting or disconnecting of delicately adjustable parts usually experienced as a part of this operation.
- 25 Another object of the invention is to provide a construction that will permit inspection and adjustment of practically all of the parts without necessitating removal of other parts to gain access thereto.
- 30 Further objects and advantages of my invention will be described hereinafter.

Figure 1 is a front view of the lower part of a piano showing my improved wind-supplying apparatus in position below the 35 key-bed;

Fig. 2 is an enlarged front view of the opposite end parts of the apparatus shown in Fig. 1, the greater part of the central section being broken away as are also other parts to reveal the arrangement of the underlying windways and valves;

Fig. 3 is a sectional end view taken upon the line 3—3 of Figs. 1 and 8;

Fig. 4 is a sectional end view taken upon 45 the line 4—4 of Fig. 2;

Fig. 5 is a sectional end view illustrating a partial disconnection of the central section of the apparatus which has been swung forwardly from operative position;

50 Figs. 6 and 7 are sectional plan views of the valve-boxes taken respectively upon the lines 6—6 and 7—7 of Fig. 2;

Fig. 8 is a rear view of the detached cen-

tral section; and Fig. 9 is a sectional view upon the line 9—9 of Fig. 2.

I have shown and will describe my invention as applied to a piano, positioned within the case thereof, and adapted to produce wind tension, but it will be understood by those conversant with the art that the following description will be equally applicable to the apparatus when installed in other kinds of musical instruments or automatic player-mechanisms contained within separate cases and may be converted to supply wind under pressure without departing from the spirit or scope of my invention.

1 designates the key-bed, 2 the sides, 3 the toe-blocks, 4 the toe-rail, 5 the bottom, 6 the sound-board, and 7 the lower front 70 panel of a piano provided with automatic player-devices located in this instance above the key-bed and not shown.

I prefer to rigidly support parts which I shall term the tension-regulating and controlling section of my improved apparatus upon the under side of the key-bed 1 and to include among such parts the devices directly connected with and controlling the windways of the said apparatus. These 80 devices are delicately adjusted and should not be disturbed or disarranged under the usual circumstances. I refer to the tension regulators or governors and to the valve-boxes; the latter being usually connected by 85 accurately adjusted mechanism with parts located in, upon, or above the key-bed.

Such parts as under usual circumstances it may be necessary to remove I prefer to support individually in the lower part of 90 the instrument and connect by flexible means with the parts hereinbefore described as rigidly supported upon the under side of the key-bed. These parts I shall term the tension creating and maintaining sections.

I provide vertically arranged support braces 14 and 14^a at each side of the center of the instrument and support-blocks 15 and 15^a between each of the braces and the adjacent side 2 of the case. These braces and 100 blocks are secured in position upon the bottom 5 of the instrument and present inclined surfaces at their forward edges which may be faced with felt or other noise-preventing material. Their lower parts may extend 105 forwardly as shown in Figs. 3, 4 and 5 or

may be provided in some other manner with supports to form cradles in which are placed the reservoir-chambers 16 and 16^a. For the purpose of supplying rigidity to the apparatus as well as to the bottom 5 and toe-rail 4, which are sometimes materially weakened by cutting away parts to accommodate the pedal connections, I extend the braces 14 and 14^a upwardly to the under side of the key-bed 1 and secure them thereto. As demonstrated by Fig. 2, the chamber 16 is supported near its lower outer edge upon block 15 and near its entire inner edge by the brace 14 and chamber 16^a is supported near its lower outer edge upon block 15^a and near its entire inner edge by the brace 14^a. These reservoir-chambers 16 and 16^a are composed of similar parts arranged laterally in reverse relative positions and a description of one of the chambers will suffice. The chamber 16^a is a shallow, rectangular, air-tight box formed of a frame 16^b and front and back sides 16^c and 16^d respectively. The members of the frame are sufficiently wide to embrace screws that may be passed through from the front of the chamber (as at 38, Fig. 2) for the purpose of securing it in position upon the support brace 14^a and block 15^a. Bolster-blocks may be secured in the air-space between the two sides 16^c and 16^d, one of such being shown at 16^e. The front side 16^c is provided with apertures 16^f which open into a reservoir of any desirable type placed upon the outer face of the side and of which I show a preferred construction comprising a movable side 16ⁱ having an opening therein fitted with a cover or "bung" 16^k, the removal of which will allow access to the interior of the reservoir and the expanding springs 16^m. Two other apertures are located at the upper part of the side, one of which 16ⁿ is for communication between the chamber and the central pumping section and the other, which is positioned under and concealed by the nipple 17, is for communication between the chamber and the chamber 18. The reservoirs and reservoir-chambers thus described constitute the tension-main-taining sections.

In the space provided between the braces 14 and 14^a and the inner edges of the chambers 16 and 16^a I locate and removably secure the pumping or tension-creating section. I have purposely eliminated such parts as would add unnecessary weight or bulk and thereby facilitate the removal of a large enough section to afford unhampered access to the lower part of the piano plate and strings. The foundation-board 19 supports upon its rear side pump-bellows having movable sides 11 hinged to swing upon their upper edges and provided with valve-ports 11^a and exterior valves 11^b. Connected with the lower edges of each movable side is

an arm 10 through which operating power may be applied by a suitable treadle mechanism. I have shown the type of treadle construction I prefer to use in Fig. 5 wherein the swinging forward of the partially disconnected central section has caused the treadles to assume the position relative thereto which exists when the section is correctly connected and the treadles folded for concealment within the case. The opening in the front panel 7 may be made wide enough to permit removal of the section as is the case in Fig. 5 or reduced to allow passage only of the treadle mechanism, which when unfolded in front of the apparatus assumes the position shown in Fig. 1. The treadle-supporting frame is pivoted at α , α to the board 19 and the treadle-links 9 are pivotally connected with the arms 10. The springs 13 are retained in position to oppose the rearward movement of the sides 11 by means of the arms 12 which are formed by bending upward and providing with screw-holes the end parts of flat strips of metal. One end of each of the arms 12 is then screwed to the front of the board 19 and the inside face of the other upturned end fitted with a block secured thereto and provided with a transverse slot for reception of the prongs of the spring 13. Along the upper edge of the board 19 I arrange and secure thereto a horizontal conduit or trunk 20, closed at the ends and extending laterally beyond the board and partially reaching over the front of the reservoir-chambers 16 and 16^a. The rear side of this trunk is provided with series of ports as at 21, 21 and 22, 22. Each of the series of ports 21 extends completely through the board 19 and open out into the interior of one of the pump-bellows and valves 23 are arranged upon the rear surface of the board over the entrance of the ports into the said bellows. Ports 22 (Figs. 2, 4 and 8) are each positioned to register when the section is in operable position with the apertures 16ⁿ in the reservoir-chambers.

Close to the inner edge of the front side 16^c of each of the chests 16 and 16^a and placed preferably at a height that will permit the forward swinging of the central section demonstrated in Fig. 5, I have secured open bearings or sockets 24, 24. Pivot pins 25, 25 are firmly secured near the opposite edges of the board 19 each pin positioned thereupon to project beyond the edge of the board and rest in the adjacent bearing 24. These pivot pins and bearings are so positioned that the central section is supported to permit registration of the ports 22 with the apertures 16ⁿ. Near the upper and lower edges of the ports 22 I bore holes in the trunk 20 and insert therethrough machine-threaded thumb-screws 26 and at corresponding locations in the chambers 16 and 130

motor. Movement of lever 37 causes the connected valve 31^a to vary the area of the port controlled thereby and change the speed of the winding devices. Movement of lever 36 causes the connected valve 30^a to vary the area of the port controlled thereby and limit the amount of direct air-tension in the action-devices. When this valve completely covers its port, air-tension continues through the indirect passage and the regulator 28. Movement of lever 35 to reverse the position of the valves connected therewith draws the valves 30^b and 30^c across their ports and thus entirely disconnects air tension from the action devices and moves the valve 31^b to open direct communication with the chamber 18 and thus permit full tension to operate the music-sheet-winding devices at maximum speed.

20 To remove the sections of the apparatus thus described the thumb-screws 26 are turned out of the bushings 27 and the central or tension-creating section is swung forward upon the pivot-pins 25 to a sufficient degree to permit lifting of the section out of the case. It may not be necessary to lift out the section in all instances for access to the rear thereof as the position shown in Fig. 5 will usually permit ordinary adjustments or repairs. Upon removal of the said section, however, the reservoir-chambers or tension-maintaining sections may be released from the supporting braces 14 and 14^a and blocks 15 and 15^a by turning out the screws 38 and removed by moving each chamber sidewise sufficiently to permit slipping of the nipples 17 from the flexible tubes 34. The chambers may then be lifted out of the case. It will thus be seen that disarrangement of the delicate adjustment of the tension-regulators 28 and 29 and the valve-boxes 30 and 31 or connections therewith is not necessary for obtaining access to the strings of plate of the piano. If desired, this entire tension-regulating and controlling section may be removed as a unit by disconnecting the devices attaching the levers 35, 36 and 37 to the valves and releasing such screws as may have been inserted through the key-bed from the upper side thereof into the valve-boxes 30 and 31 or other supporting means attached to the chamber 18.

Having thus described my invention, I claim:

5 1. Wind-supplying apparatus comprising, in combination, a plurality of pump bellows arranged side by side, supports, reservoir chambers arranged one at each side of said bellows and secured to said supports, and a conduit or chamber communicating with said bellows and detachably secured to and in communication with said reservoir chambers.

65 2. Wind-supplying apparatus comprising,

in combination, a plurality of pump bellows arranged side by side, a support, a reservoir chamber provided with a movable reservoir member arranged at the side of said bellows and secured to said support, and a conduit or chamber communicating with said bellows and detachably secured to and in communication with said reservoir chamber.

3. Wind-supplying apparatus comprising, in combination pump bellows, a support, a reservoir-chamber arranged at the side of said bellows and secured to said support, a conduit or chamber secured in communication with said bellows to form therewith a single removable unit, extending horizontally therefrom and detachably secured in communication with said reservoir-chamber, and means for removably securing said bellows and said conduit or chamber in position to hold said conduit or chamber in communication with said reservoir-chamber.

25 4. Wind-supplying apparatus comprising, in combination, a support, a reservoir chamber provided with a movable reservoir member and secured to said support, and a pumping device located apart from and at the side of said chamber, removably secured in position with relation thereto and detachably secured to and in communication therewith.

5. Wind-supplying apparatus comprising, in combination, a support, a reservoir chamber provided with a movable reservoir member and secured to said support, a pumping device apart from said chamber and detachably secured to and in communication therewith, and means for removably securing said device in position at the side of said chamber.

105 6. Wind-supplying apparatus comprising, in combination, a support, a reservoir chamber provided with a movable reservoir member and secured to said support, a pumping device located apart from and at the side of said chamber and removably secured in position with relation thereto, and means for detachably securing said device to and in communication with said chamber.

7. Wind-supplying apparatus comprising, in combination, a support, a reservoir chamber provided with a movable reservoir member and secured to said support, and a plurality of pump bellows arranged side by side apart from and at the side of said chamber, removably secured in position with relation thereto and detachably secured to and in communication therewith.

110 8. Wind-supplying apparatus comprising, in combination, a support, a reservoir chamber provided with a movable reservoir member and secured to said support, a pumping device located at the side of said chamber apart therefrom and removably secured in position with relation thereto, and a con-

16^a I insert interior and exterior threaded metal bushings 27. As shown in Fig. 4, the upper bushings may extend through the front side of the chambers and be received by the frame 16^b and the lower bushings 16^c may likewise be received by bolster-blocks 16^e. The rear surface of the extending ends of the trunk 20 may be covered with leather or a similarly useful substance for packing about the port 22 and it will thus be seen that by turning the thumb-screws 26 into the threaded bushings 27 an air tight communication may be established between the chambers 16 and 16^a by the trunk 20 with the pump-bellows of the central section.

17 I shall now describe the tension-regulating and controlling section. This section consists of the horizontally disposed chamber 18, action wind tension-regulator 28, 20 motor wind tension-regulator 29, action valve-box 30, and motor valve-box 31.

18 The chamber 18 is formed by upper, lower, front and rear sides and end blocks preferably secured together to form a solid 25 unit. Bolster-blocks may be located at different points in the chamber to prevent warping of the upper and lower sides. Openings 32 and 32^a are located in the lower side to afford communication with the chambers 16 and 16^a respectively, connection being made by means of nipples 33 and 17 and flexible tubes 34. At either end of the upper side I place the valve-boxes 30 and 31 for controlling the different degrees of wind- 30 tension for the pneumatically operable parts of the instrument. The boxes are removably secured in position upon the chamber and I prefer to construct them substantial enough to sustain the chamber 18 rigidly 35 in position when they are in turn held to the under side of the key-bed. Other supports may of course be used if desirable. The specific construction of the valve-boxes 30 and 31 and the tension-regulators 28 and 40 29 do not constitute a part of this invention and I shall but briefly describe their functions, it being understood that any desirable type of either of these devices may be used. Other constructions either of the instru- 45 ment or the devices mentioned may warrant different positioning and manner of connection of the devices with chamber 18. The chamber 18 is supplied with ports 18^a and 18^b in its upper side and 18^c and 18^d in 50 its lower side. In constructing the chamber the end blocks 18^e and 18^f are extended inwardly a sufficient distance to produce solid ends which may permit passages therethrough to open out in desired positions 55 upon the upper and lower faces of the chamber. I have shown an "offset" in the passages 18^b and 18^c to demonstrate the accommodation of regulators and valve-boxes with ports not correspondingly located.

60 65 The action valve-box 30 is supplied in its

lower side with ports positioned to register with the port 18^a and the upper opening of passage 18^b of the chamber and in its upper side with the port 30^a for communication through the key-bed with the action devices 70 located thereabove. The motor valve-box 31 is supplied in its lower side with ports positioned to register with the port 18^b and the upper opening of passage 18^c of the chamber and in its front side with the port 75 31^a for communication in any desired manner with the music-sheet-winding wind-motor usually located in the upper part of the instrument. Controlling slide-valves are positioned in the boxes to be moved 80 over or from adjacent ports. The valves 30^b and 30^c in valve-box 30 and valve 31^b in valve-box 31 are connected for movement with the lever 35 so that movement of the lever in one direction slides the valves 30^b 85 and 30^c over their ports and the valve 31^b away from its port. Reverse movement of the lever causes reverse valve operation. Valve 30^d is connected for movement with the lever 36 and preferably is held normally 90 away from its port as shown in the drawings. Valve 31^c is connected for movement with the lever 37.

95 The tension-regulator 28 is connected with variable air-tension in the chamber 18 through the port 18^e and causes air-tension regulated by the strength of the spring 28^a (Fig. 2) in the passage 18^b. The construction and action of tension-regulator 29 is similar to that of 28, being connected with 100 variable tension through the port 18^c and causing regulated tension in the passage 18^c.

105 Operation of the treadles forces the sides 11 of the pump-bellows connected therewith against the opposition of springs 13 to draw 110 air from the spring-expanded reservoirs of the chambers 16 and 16^a through the apertures 16^f and 16^g of the chambers, ports 22 and 21 of the trunk 20 into the pump-bellows past the check-valves 23. Air is prevented 115 from returning through the ports 21 by the said valves 23 and is expelled by the collapse of the pump-bellows through the valve-ports 11^a. The same degree of air-tension is maintained in the chamber 18 as in the 120 chambers 16 and 16^a through the flexible connections 34 hereinbefore described. With the controlling-valves in the positions shown in Fig. 2, air-tension may be created in the pneumatic action devices (not shown) through 125 the port 18^a past both of the valves 30^b and 30^c and through the port 30^a without restriction and also through port 18^b, regulator 28, passage 18^b, past the valve 30^b, and so through the port 30^a, while tension may be created 130 in music-sheet-winding devices through the port 18^c, regulator 29, passage 18^c, past the valve 31^c, and through the port 31^a. Full air-tension would thus be created in the action devices and regulated tension in the 135

secured in position with relation thereto and communicating with said first chamber through said second chamber.

33. Wind-supplying apparatus comprising, in combination, a first chamber (18), a second chamber (16) located below and communicating with said first chamber, a plurality of pump bellows arranged side by side below said first chamber apart from 5 and at the side of said second chamber, removably secured in position with relation to said second chamber and communicating with said first chamber through said second chamber.

34. Wind-supplying apparatus comprising, in combination, a first chamber (18), a support (14), a second chamber (16) located below and communicating with said first chamber and secured to said support, 10 and a pumping device located below said first chamber apart from and at the side of said second chamber, removably secured in position with relation to said second chamber and communicating with said first chamber 25 through said second chamber.

35. Wind-supplying apparatus comprising, in combination, a first chamber (18), a support (14), a second chamber (16) located below said first chamber and detachably secured in communication therewith, a pumping device located below said first chamber apart from and at the side of said second chamber, removably secured in position with relation to said second chamber 30 and communicating with said first chamber through said second chamber, and means for removably securing said second chamber to said support.

36. Wind-supplying apparatus comprising, in combination, a first chamber (18), a reservoir chamber located below and communicating with said first chamber and provided with a movable reservoir member, and a pumping device located below said first 45 chamber apart from and at the side of said reservoir chamber, removably secured in position with relation to said reservoir chamber and communicating with said first chamber through said reservoir chamber.

37. Wind-supplying apparatus comprising, in combination, a first chamber (18), two chambers secured in position to provide an intervening space therebetween below said first chamber, one of said two chambers 50 communicating with said first chamber, and a pumping device located in the intervening space apart from said two chambers, removably secured in position with relation thereto and communicating with said first chamber through one of said two chambers.

38. Wind-supplying apparatus comprising, in combination, a first chamber (18), two chambers positioned to provide an intervening space therebetween below said 55 first chamber, one of said two chambers be-

ing detachably secured in communication with said first chamber, a pumping device located in the intervening space apart from said two chambers, removably secured in position with relation thereto and communicating with said first chamber through one of said two chambers, and means for removably securing one of said two chambers in position. 70

39. Wind-supplying apparatus comprising, in combination, a first chamber (18), two chambers positioned to provide an intervening space therebetween below said first chamber, one of said two chambers being removably secured in position with relation to 80 said first chamber, a pumping device located in the intervening space apart from said two chambers, removably secured in position with relation thereto and communicating with said first chamber through one 85 of said two chambers, and means for detachably securing one of said two chambers in communication with said first chamber.

40. Wind-supplying apparatus comprising, in combination, a first chamber (18), 90 two chambers positioned to provide an intervening space therebetween below said first chamber, means for removably securing one of said two chambers in position and detachably securing one of said two chambers 95 in communication with said first chamber, and a pumping device located in the intervening space apart from said two chambers, removably secured in position with relation thereto and communicating with said first 100 chamber through one of said two chambers.

41. Wind-supplying apparatus comprising, in combination, a first chamber (18), two chambers secured in position to provide an intervening space therebetween below said first chamber, one of said two chambers communicating with said first chamber, and a plurality of pump bellows arranged side by side in the intervening space apart from said two chambers, removably secured 110 in position with relation thereto and communicating with said first chamber through one of said two chambers.

42. Wind-supplying apparatus comprising, in combination, a first chamber (18), a support (14), two chambers positioned to provide an intervening space therebetween below said first chamber, one of said two chambers communicating with said first chamber and secured to said support, and a 115 pumping device located in the intervening space apart from said two chambers, removably secured in position with relation thereto and communicating with said first chamber through one of said two chambers. 120

43. Wind-supplying apparatus comprising, in combination, a first chamber (18), a support (14), two chambers positioned to provide an intervening space therebetween below said first chamber, one of said two 130

- chambers being detachably secured in communication with said first chamber, a pumping device located in the intervening space apart from said two chambers, removably secured in position with relation thereto and communicating with said first chamber through one of said two chambers, and means for removably securing one of said two chambers to said support.
- 10 44. Wind-supplying apparatus comprising, in combination, a first chamber (18), two reservoir chambers secured in position to provide an intervening space therebetween below said first chamber, one of said two chambers being provided with a movable reservoir member and one of said two chambers communicating with said first chamber, and a pumping device located in the intervening space apart from said two chambers,
- 15 20 removably secured in position with relation thereto and communicating with said first chamber through one of said two chambers.
45. In a pneumatic music playing instrument, the combination of a pneumatic valve action, wind-supplying apparatus, an air passage (30^a) extending between said action and said apparatus and adjustable means (35, 36) for controlling said passage; said apparatus comprising a first chamber (18) associated with said passage, a second chamber detachably secured in communication with said first chamber, a pumping device apart from said second chamber detachably secured in communication with said first chamber through said second chamber, means for removably securing said second chamber in position below said first chamber and means for removably securing said device in position below said first chamber at
- 25 30 35 40 the side of said second chamber.
46. In a pneumatic music playing instrument, the combination of a pneumatic valve action, wind-supplying apparatus, an air passage (30^a) extending between said action and said apparatus and adjustable means (35, 36) for controlling said passage; said
- apparatus comprising a first chamber (18) associated with said passage, a second chamber located below said first chamber and removably secured in position with relation thereto, a pumping device located below said first chamber at the side of said second chamber and removably secured in position with relation to said second chamber, means for detachably securing said second chamber in communication with said first chamber and means for detachably securing said device in communication with said first chamber through said second chamber.
47. The combination, in vacuum producing apparatus for musical instruments, of the outer casing, the wind chest, suction bellows attached to and below the latter, pedals connected to said suction bellows and located directly in front of the same, and a swinging hanger for said pedals pivotally connected to the front of the bellows, whereby it, with its pedals, can be folded up in front of the suction bellows beneath the wind chest and inside the casing of the instrument.
48. The combination, in vacuum producing apparatus for musical instruments, of the outer casing, a wind chest, suction bellows attached to and below the latter, pedals connected to the movable members of the suction bellows and located directly in front of the same, and a pedal hanger pivotally mounted upon the front members of the suction bellows so as to swing up against the same, carrying the pedals with it, whereby the entire pedal structure can be folded up in front of the suction bellows beneath the wind chest and inside the casing of the instrument.

Signed at Chicago, Illinois, this thirteenth day of February, 1908, in the presence of two subscribing witnesses.

JAMES CLARKE HAGEY.
